UNITED STATES PATENT OFFICE.

ALBERT J. DAVIES, OF KENOGAMI, QUEBEC, CANADA.

FOURDRINIER MACHINE.

1,220,611.

Specification of Letters Patent. Patented Mar. 27, 1917.

Application filed January 5, 1916. Serial No. 70,402.

To all whom it may concern:

Be it known that I, ALBERT J. DAVIES, of Kenogami, in the Province of Quebec, a citizen of the United States, and residing at 5 the above place in the Dominion of Canada, have invented certain new and useful Improvements in Fourdrinier Machines, of which the following is a specification.

This invention relates to paper making 10 machines of the Fourdrinier type and is in the nature of an improvement on my U. S. Pat. No. 1,090,974, issued Mar. 24, 1914, to which reference may be had. This patent is adapted for use where the side rails or 15 bars are arranged in pairs and is acceptable for that form of construction.

The present invention is adapted for application to those forms of machine where a single fixed side bar is used and comprises 20 an arrangement whereby the reciprocating movement of each suction box is independent from that of any other.

In the drawings which accompany and 25 form part of this specification,—

Figure 1 is a diagram of a portion of a Fourdrinier machine.

Fig. 2 is an enlarged side view showing 30 two boxes and their mountings, partly in section.

Fig. 3 is a partial cross-section on line 3—3 of Fig. 2.

The frame 1, "Shaker rail" 2, Deckel strap 3, breast roll 4 and couch rolls 5, 5 are of the usual construction and need no 35 detailed description.

The suction boxes 6 are provided with 40 flexible suction tubes 7, connected to the ordinary manifold 8, and are adapted to closely underlie the apron of wire cloth 9, with room for a certain amount of end play.

The means for movably mounting boxes 6 between fixed rails 10 form the principal subject matter for this invention and my preferred form may be described as follows,—

At about the center of each rail 10 and opposite the ends of boxes 6 I form a perforation 12 adapted to loosely receive a tongue 13, fast on a cover-plate 14 and bored to 50 closely receive bolts 15 which pass upward through bosses 16 of a casting 17, the latter being secured to box 6 by screws 18.

Round-headed nuts 19 will permit some 55 vertical adjustment of box 6, as by shims 20, seen in Fig. 3.

A pivotal bearing 21, fast on casting 17, provides a connection for eccentric rod 22 and an eccentric 23 on a driving shaft 24. A pulley 25 is a possible means for transmitting power to shaft 24.

On the upper surface of rail 10 and adjacent to perforation 12, I provide pockets 26 whose bottoms are lined with steel or phosphor-bronze bearing plates 27 to support a series of rolls 28 or, if desired, a nest of balls may be substituted, as the desirable feature of this bearing is to provide a rolling support for plate 14. Overlying rolls 28 are bearing plates 29, nested within suitable recesses 30 in plate 14; and overhanging lips 31, on the latter, tend to exclude moisture.

It will be noticed that whereas the rails 10 are preferably inclined, the pockets 26 are level and the thrust of motion is equally 75 distributed over the bearing surfaces of the rolls 28.

I do not limit myself to the precise construction shown.

What I claim is:—

1. In a machine of the Fourdrinier type, a fixed side rail with an opening; a cover plate overlying said opening and provided with a tongue adapted to loosely occupy said opening; a suction box adapted to be 85 secured to said tongue; and means for transversely reciprocating said box.

2. A fixed rail with an opening; a cover plate adapted to overlie said opening; a tongue fast on said plate and adapted to 90 loosely occupy said opening; an anti-friction bearing for said plate; and means for causing reciprocating movements of said cover plate.

3. In a machine of the Fourdrinier type, a pair of side rails each provided with an opening; a suction box; a pair of cover plates overlying said openings and each provided with a depending tongue adapted to loosely occupy one of said openings; anti-friction bearings interposed between said rails and said cover plates; means for attaching said box to said tongue; and means for causing relative movement between said box and rails.

4. In a machine of the Fourdrinier type, a fixed rail; a suction-box; movable means for mounting said box in guided relation to said rail; and mechanism for transversely reciprocating said means.

5. In a machine of the Fourdrinier type, a fixed rail; a suction-box; movable means, fast on said box, whereby said box is supported by said rail; anti-friction bearings for said means; and mechanism for trans-
5 versely reciprocating said means.

In testimony whereof, I have affixed my signature in the presence of two witnesses.

ALBERT J. DAVIES.

Witnesses:

A. T. PALMER,
WALLIS L. BUISEY.
